YORK, A CORPORATION OF NEW YORK

ELECTRIC SWITCH

Application filed September 21, 1927. Serial No. 221,099.

For a detailed description of the present form of our invention, reference may be had to the following specification and to the accompanying drawings forming a part thereof, 5 wherein

Figs. 1 and 2 show plans of our switch in its closed and open conditions respectively.

Our invention relates to a limit switch of the toggle type with a specially arranged 10 lever for maintaining substantial pressure on the abutting contacts beyond the instant when the toggle breaks, so as to avoid arcing by reason of the chattering of the contacts one upon the other as the toggle flattens.

15 Referring to the drawings, A represents the stationary and B the movable contact. The latter consists of a metal cylinder with top and bottom trunnions which are pivoted respectively in the end of lever C and a similar 20 and parallel lever beneath which is not shown. The levers C serve as an independent mounting or carrier for contact B apart from its actuating agencies. A sliding rod D passes diametrically through said contact B and at 25 its inner end is jointed between the ends of parallel levels F. Levers F and rod D constitute the two members of the toggle. The levers F are connected by link G to parallel levers H, which are pivoted on frame-plate K 30 at the point H² and are also jointed to push-rod P. The frame-plate K is seated on the insulating base R and has two upturned abutments K² and K³ on its opposite edges. A spring E surrounding rod D tends to force 35 the said rod away from contact B through which it extends and a spring Q tends to force push-rod P outwards away from abutment K² against which the spring Q abuts.

When the switch is in its normal closed 40 condition as shown in Fig. 1, the spring E tends to force the movable contact B on the end of lever C against the stationary contact A, the spring reacting against levers F which, in turn, react through link G and levers H 45 against the abutment K³. To throw the switch to its open position, shown in Fig. 2, pressure is applied to the push-rod P against the force of spring Q. The immediate effect 50 of this pressure, acting through levers H, link G and levers F, is to compress spring E

and thereby increase the pressure of contact B against stationary contact A. This pressure continues as the push-rod P is moved inward and the toggle is gradually flattened. As the toggle flattens and rod D protrudes 55 further and further through contact B, the contact B is being rotated by the rod D and has a rubbing or grinding effect on contact A although the two contacts are not separated but are still pressed forcibly together. It will be observed that the carrier C and the toggle member F are pivoted to the plate K, 60 so as to move on adjacent axes on arcs which are not concentric. Therefore, the toggle must straighten and pass the line between the pivot of the carrier C and the axis of rotation of the contact B before it can move said carrier, and as shown, the toggle must break before it reaches this position. As a result, the pressure of contact B against the contact A 65 will continue even when the toggle is completely flattened and in fact until after the instant when the toggle breaks and snaps over dead centre causing the contacts to fly apart. Since the switch is designed to serve as a 70 limit switch it will remain open only so long as pressure is maintained on push-rod P. When that pressure is released, the superior power of spring Q will instantly restore it to its normal closed condition. The advantage 75 of the maintained pressure on the contacts up to and beyond the instant of break is to avoid arcing by chattering of the contacts one upon the other as the toggle flattens. The flattening of the toggle compresses the spring E at 80 first, and thereby maintains the contact pressure up to and beyond the instant of break and also has force stored in it which, on release will spread the contacts apart. By this 85 means a separate spring i. e. separate from the main spring Q, performs the aforesaid functions, which in ordinary practice are imposed on one main spring, such as the spring Q.

What we claim as new and desire to secure by Letters Patent is:

1. An electric switch comprising a stationary contact, a contact carrier, a contact movably supported by said carrier, a spring toggle having one arm movably engaging said movable contact, and operating means for said 100

toggle, said contact carrier and said toggle being independently and movably supported in adjacent positions, so that the contacts will be maintained in engagement beyond the 5 breaking point of the toggle.

2. An electric switch comprising a stationary contact, a contact carrier, a contact movably supported by said carrier, a toggle having one member extending through said 10 movable contact and movable with respect thereto, a spring interposed between said movably mounted contact and the joint of said toggle, and operating means for said toggle, said contact carrier and said toggle 15 being independently and movably supported in adjacent positions, so that the contacts will be maintained in engagement beyond the breaking point of the toggle.

3. An electric switch comprising a stationary contact, a contact carrier, a contact movably supported by said carrier, a spring toggle having one arm movably engaging said 20 movable contact, means normally acting to move the toggle in one direction, and means 25 for temporarily imparting movement to the toggle in the opposite direction, said contact carrier and said toggle being independently and movably supported in adjacent positions so that the contacts will be maintained in 30 engagement beyond the breaking point of the toggle.

4. An electric switch comprising a stationary contact, a movable carrier, a contact rotatably mounted in said carrier, an actuating 35 spring toggle, means for imparting movement to the toggle, one member of said toggle having a slidable engagement with said rotatably mounted contact, and means for movably supporting said carrier and said toggle in 40 adjacent positions, so that engagement of said contacts will be maintained beyond the breaking position of the toggle.

5. An electric switch of the character described comprising a stationary contact, a 45 pivoted carrier, a cylindrical contact rotatably supported by said carrier, an actuating toggle, and means for imparting movement to said toggle, one member of said toggle 50 being extended through and having slidable engagement with said cylindrical contact, means for supporting the carrier and the toggle in adjacent positions, so that engagement of said contacts will be maintained beyond the breaking position of the toggle, and a spring interposed between said cylindrical contact and the joint of the toggle.

Signed at Albany, county of Albany, State of New York, this 29th day of August, 1927.

60 OSCAR LORENZO.
JOHN W. CONWAY.
